UNITED STATES PATENT OFFICE

149,458

DESIGN FOR A CABINET FOR A FILM PROJECTION UNIT CONSTITUTING VISUAL TRAINING AND MECHANICAL GAME DEVICE

John Tjaarda, Grosse Pointe Shores, Mich., assignor, by mesne assignments, to Training Devices, Inc., Detroit, Mich., a corporation of Michigan

Application March 9, 1946, Serial No. 127,317

Term of patent 14 years

(Cl. D61—1)

To all whom it may concern:

Be it known that I, John Tjaarda, a citizen of the United States, residing at 884 Lakeshore Drive, Grosse Pointe Shores, in the county of Wayne and State of Michigan, have invented a new, original, and ornamental Design for a Cabinet for a Film Projection Unit Constituting Visual Training and Mechanical Game Device, of which the following is a specification, reference being had to the accompanying drawing, forming part thereof.

Figure 1 is a perspective view of a cabinet for a film projection unit constituting visual training and mechanical game device, showing my new design;

Figure 2 is a front elevational view thereof; and

Figure 3 is a side elevational view thereof.

I claim:

The ornamental design for a cabinet for a film projection unit constituting visual training and mechanical game device, as shown.

JOHN TJAARDA.
